DRAINAGE TUBE WITH CLOT EXTRACTOR

Charles F. Recklitis, Mahanoy City, Pa.

Application October 24, 1951, Serial No. 252,888

6 Claims. (Cl. 27—24)

1

This invention relates to embalming instruments and in particular to a drainage tube with a clot extractor.

Upon death the blood leaves the arteries completely and is found only in the veins. Unless the blood supply is withdrawn from the veins while an embalming fluid is being injected into the arteries, discoloration and puffing of the body will result.

In the usual embalming practice an elongated tube is inserted into one of the large and readily accessible veins. The axillary vein is best for this purpose, because when the arm is extended there is alignment with the subclavian vein, so that the tube may be introduced to a point near the junction with the internal jugular vein. At this point, the blood vessels are materially larger than the tube and provide good clearance for a free flow of blood.

The operation is quite simple when the blood flows freely without interruption. In some cases, however, large, soft clots and stringy fibrin are found, which if not removed will clog the inlet of the drainage tube and prevent the flow of blood. As it is practically impossible to remove the drainage tube for cleaning and reinsert it in the vein, the removal of blood clot and fibrination without withdrawal of the drainage tube presents a very important problem.

While various types of implements have been proposed and used for this purpose, none of them completely solves all the problems involved. A plunger mechanism that must be completely withdrawn to a certain point to insure a normal flow, which withdrawal causes an undue elongation of the tube making it inconvenient to handle, is a source of continued annoyance to the embalmer during operation. Where the complete withdrawal of the plunger mechanism leaves the tube opening completely exposed to the sudden onrush of blood following clot extraction, there is usually considerable danger of spillage.

Those implements for breaking up the clot at the inlet end of the tube without its removal often involve risk in use because failure to accomplish this requires removal from the vein of the drainage tube with the almost insurmountable difficulty of either reinsertion or establishing an alternative discharge flow of the blood supply.

The general purpose of this invention is to provide a drainage tube with a clot extractor constructed and arranged to control the outlet flow of blood during insertion of the implement

2

in the vein and withdrawal of a clot through the drainage tube while the implement is inserted, and to offer a minimum of obstruction and interference to the embalmer in use.

A specific object of the invention is to provide a drainage tube having a rotatable and slideable inner tube providing the clot extracting means and also the valve means for controlling the discharge of blood through the tube. Another inventive object resides in the provision of a drainage tube with clot extracting means that provides for vein expansion, substantially free normal flow of blood, and adequate control of blood discharge during a clot removal operation.

It is a further purpose of this invention to provide a simple, easily cleanable, relatively short in overall length drainage tube with clot extractor.

These and other objects contributing to efficiency and satisfaction in use will be more fully understood from the following detailed description of a preferred embodiment of the invention, when taken in connection with the accompanying drawing, in which:

Fig. 1 is a side elevation of the embalming implement of this invention, with the parts in the relative positions occupied when the implement has been inserted in a vein and blood is being discharged under normal conditions;

Fig. 2 is a vertical section of the right-hand portion of the implement as shown in Fig. 1, with certain parts broken away;

Fig. 3 is a vertical section of the forward or left end of the implement of Fig. 1, but showing the relation of certain parts either for insertion into a vein or the initial movement of clot withdrawal while the implement is in the vein;

Fig. 4 is a cross-sectional view taken on line 4—4 of Fig. 3; and

Fig. 5 is a cross-sectional view of the implement taken on line 5—5 of Fig. 2.

The embalming implement illustrated in the drawing is of all metal construction, with the parts being formed preferably from stainless steel where practical.

As shown in Figs. 1 and 2, this implement comprises an outer tube 10 receiving in slideable and rotatable relation an inner tube 12 that is substantially coextensive therewith. A delivery or outlet tube 14 is secured in rearward angular relation to the rearward end portion of outer tube 10 by means of an integrally connected sleeve 16, which sleeve may be brazed or otherwise secured on the outside of tube 10.

It will be noted in Fig. 2 that the outer tube

10 is formed with an aperture or opening 18 of oval shape aligned with an adjacent opening 20 formed by the inner end of the outlet tube 14. The other end of the angularly disposed outlet tube 14 may have a nipple formation 22 for retaining a rubber tube leading therefrom to a collecting vessel. The corresponding end portion of the inner tube 12 is formed with an alignable oval opening 24 that is relatively movable to act as a valve controlling discharge through the delivery tube 14.

In the illustrative implement the rearward end of the outer tube 10 has a union sleeve 26 secured as by brazing over the end portion thereof. The sleeve 26 has an outer end comprising an externally threaded portion 28 for receiving a retaining cap 30 formed with an internally threaded end portion 32, and a bore portion 34 slidably accommodating the inner tube 12. A knobbed end formation 36 secured to the end of the inner tube 12 provides abutment means for limiting the insertion of the tube 12 within the tube 10 to a position in which openings 20 and 24 are aligned as shown.

At the open or forward end, the inner tube 12 has a plurality of spaced, clot-engaging, spring fingers 38 formed integrally therewith and extending in a generally longitudinal direction. It is essential that these three resilient fingers or prongs 38 have good springiness so that they will open from the retracted position within tube 10 shown in Fig. 3 to the extended or expanded position illustrated by Fig. 1. The outer end portions of the spring fingers 38 are arcuate and outwardly curved with the end extremities inverted for gripping and withdrawing as clearly shown.

In order to facilitate initial insertion of the forward end of the implement in the slit made in the vein to be used for draining, the open end of the outer tube end 10 is formed with a fairly sharp beveled edge.

It is believed that the advantages of this novel form of drainage tube with clot extractor can best be demonstrated by a detailed description of the manner in which it is to be used.

When the outer drainage tube 10 is inserted in a vein slit, the spring fingers 38 will retract and compress within the outer or forward portion end of tube 10 as shown in Fig. 3. In this position there is appreciable opening for flow through the inner tube 12, as will be understood from a consideration of Fig. 4. In this relation of the fingers 38, the inner tube 12 will have been withdrawn by means of the knob 36 so that it extends only approximately one inch beyond the closed end of the tube 10 at the extremity of the retaining cap 30. Such withdrawing movement will have carried the opening 24 of the inner tube 12 past the opening 20 of the delivery tube 14 so that no discharge flow is possible.

After the tube 10 is within the vein, the inner tube 12 will be advanced or inserted by appropriate movement of the knobbed end 36 so that the spring fingers 38 will be released and permitted to expand in a way providing a substantial opening or cross section for the adjacent wall portion of the vein. The delivery or outlet tube 14 will at this time be opened to flow by longitudinal and angular alignment of the lateral opening 24 of the inner tube 12 therewith. This last mentioned relation is clearly shown in both Figs. 2 and 5.

It will also be understood that discharge flow

can be controlled by suitable rotation of the inner tube 12, by means of the knob 36, to a position that will close the entrance to the outlet tube 14.

5 When a mass clot or fibrillation lodges on the end portions and within the fingers 38, with a consequent reduction or stoppage of blood flow, it can be readily removed by retraction of the inner tube 12, operated by the knob 36 with the outer tube 10 being retained in position in the vein by being held against movement with the inner tube 12. During this retraction or withdrawal movement of the inner tube 12, the opening of the outlet or delivery tube 14 will 10 be closed by the solid wall portion of the inner tube 12, so that there will be complete and continuous control of blood flow, with no danger of spillage. The rearward or inner end of the outer tube 10 is closed at all times, when the inner tube opening 24 is within the outer tube 10 and its sleeve 26 and cap 30 extension.

While in most instances there will be little or no flow of blood through the implement when the inner tube 12 is clamped over a clot and 25 being withdrawn toward the rearward end, as soon as the opening 24 in the side of the inner tube 12 is exposed beyond the retaining cap 30 it can readily be closed by application of a finger thereto. The distance from the inner end opening 20 of the outlet tube 14 to the rearward opening of the structure of outer tube 10 is made sufficiently greater than the length of the fingers 38 that a relatively large free flow of blood 30 can be established through the outlet tube 14 before the clot is removed from the relatively 35 more remote and smaller opening of the bore portion 34.

These arrangements and operation provide all the required safe guard that is needed against 40 spillage from the rearward end of the implement. It will also now be understood that when in the usual operation of the implement a clot is not being removed, the overall length and particularly the extent of rearward projection 45 of the implement have been reduced to a minimum. The rotatable movement of the inner tube 12 affords control of the opening of outlet tube 14 in this condition of minimum rearward projection.

50 While a preferred embodiment of this invention has been fully described, it will be understood by those skilled in the art that numerous changes can be made in the details of construction and arrangement of parts without departing from the spirit of this invention and the scope of the appended claims.

Having thus described my invention, what I claim as novel and desire to secure by Letters Patent of the United States is:

60 1. An embalming implement comprising an outer tube formed with a lateral opening in one end portion, an inner tube slidably and rotatably fitted within the outer tube and formed with a lateral opening alignable with the lateral opening 65 in the outer tube, the end of the inner tube adjacent its lateral opening being closed and its other end being open, and a plurality of resilient prongs on the other end of the inner tube constructed and arranged to be received within the outer tube and to project in expanded relation beyond the outer tube when said lateral openings are aligned.

70 2. An embalming implement comprising an outer tube formed with a lateral opening in one end portion, a substantially coextensive inner

tube slidably fitting and rotatable within the outer tube and formed with a lateral opening alignable with the lateral opening in the outer tube, the end of the inner tube adjacent its lateral opening being closed and its other end being open, and a plurality of spring fingers integral with the other end of the inner tube, said fingers being constructed and arranged to retract within the outer tube and to project in expanded relation therebeyond when said lateral openings are aligned.

3. An embalming implement comprising an outer tube formed with a lateral opening adjacent one end, a substantially coextensive inner tube slidably fitting and rotatable within the outer tube and formed with a lateral opening alignable with the lateral opening in the outer tube, the end of the inner tube adjacent its lateral opening being closed and its other end being open, and a plurality of outwardly arcuate spring fingers with inturned ends on the other end of the inner tube and arranged to project in expanded relation beyond the outer tube when said lateral openings are aligned.

4. A drainage tube with clot extractor for embalming use, comprising an outer tube formed with a lateral opening in a rearward end portion, a delivery tube secured to the outer tube as an extension of the lateral opening therein, an inner tube having an opening alignable with the delivery tube slidably and rotatably mounted in the outer tube and extending substantially the length thereof, the rearward end of the inner tube being closed and its forward end being open, and a plurality of resilient fingers on the forward end of the inner tube adapted to project beyond the forward end of the outer tube in expanded relation when said lateral openings are aligned.

5. A drainage tube with clot extractor for embalming use, comprising an outer tube formed with a lateral opening in one end portion and having the edge of its opposite end beveled, a delivery tube secured to the outer tube as an angular extension of the lateral opening therein, an inner tube having an opening alignable with the

delivery tube slidably and rotatably mounted in the outer tube and extending substantially the length thereof, the end of the inner tube adjacent the delivery tube being closed and being provided with an abutment formation limiting insertion of the inner tube and its other end being open, and a plurality of spaced spring fingers formed on the other end of the inner tube and adapted to project beyond the beveled edge of the outer tube in expanded relation when the inner tube is inserted as far as permitted by said abutment formation.

6. A drainage tube with clot extractor for embalming use, comprising an outer tube formed with a lateral opening in a rearward end portion and having the edge of its forward end beveled, a delivery tube secured to the outer tube as a rearward angular extension of the lateral opening therein, an inner tube having an opening alignable with the delivery tube slidably and rotatably mounted in the outer tube and extending substantially the length thereof, the rearward end of the inner tube being closed and being provided with an abutment formation limiting insertion thereof and its other end being open, and a plurality of spaced spring fingers having end portions with inturned ends formed on the forward end of the inner tube and adapted to project beyond the forward end of the outer tube in expanded relation when the inner tube is inserted as far as permitted by said abutment formation, said fingers being of less length than the distance of the lateral opening in the outer tube to the rearward end of said outer tube.
